UNITED STATES PATENT OFFICE.

DANIEL SMITH, OF GRIFFIN CORNERS, NEW YORK.

GAME APPARATUS.

SPECIFICATION forming part of Letters Patent No. 694,799, dated March 4, 1902.

Application filed March 28, 1901. Serial No. 53,207. (No model.)

To all whom it may concern:

Be it known that I, DANIEL SMITH, a citizen of the United States, and a resident of Griffin Corners, in the county of Delaware and State 5 of New York, have invented a new and Improved Game Apparatus, of which the following is a full, clear, and exact description.

This invention relates to a game apparatus constituting a miniature bowling-alley arranged so that it may be conveniently employed in any room of a dwelling, to which end the invention comprises a table of convenient size with certain especially-arranged devices for enabling the game to be played.

15 This specification is a specific description of one form of the invention, while the claims are definitions of the actual scope thereof.

Reference is to be had to the accompanying drawings, forming a part of this specification, 20 in which similar characters of reference indicate corresponding parts in all the views.

Figure 1 is a perspective view of the invention. Fig. 2 is a horizontal section of the ball-projector, the view being taken on the line 2 2 25 of Fig. 3, and Fig. 3 is a section on the line 3 3 of Fig. 2.

a represents a table which has legs b b' for sustaining it, the legs b being pivotally attached to the table and the legs b' being pivotally carried on the legs b and adapted to be adjustably engaged with the table through the medium of cleats a', fastened on the under side of the table, as shown by the dotted lines in Fig. 1. By adjusting the legs b the inclination of the table may be regulated. The table comprises on its upper face a smooth surface or run a², over which the balls are rolled and at each side of which are grooves or passage-ways a³, serving to carry the balls back to the point from which they are thrown. The pins (indicated at c in the drawings) are adapted to be set at one end of the run a², just at the mouth of an inclosure d, formed at the adjacent end of the table. This inclosure is 45 designed to receive the pins that are knocked down, as well as the balls which are shot against them.

d' represents a hinged lid, by raising which access may be had to the inclosure d. If desired, this lid d' may be provided with a tablet or other device for keeping the score of the game.

At the other end of the table is arranged a device for throwing the balls, which device is carried on a transverse bar e, attached to the 55 table, and it comprises a body portion f, with a cap f' fastened thereto. This cap has a groove f² formed in its under side, and this groove receives the bar e, permitting the ball-projector to be rocked on the bar e, so as to 60 aim at the pins. A plunger f³ is mounted horizontally in the body f of the projector and has at one end a finger-piece f⁴ and at the other end a seat f⁵ for the ball, which is indicated by dotted lines in Fig. 3 and shown 65 by full lines in Fig. 1. An expansive spring f⁶ serves to throw the plunger f³ from the position shown in Fig. 3 to its rightward position, or, in other words, until the shoulder of the finger-piece f⁴ strikes the body f. This 70 shoulder may be cushioned, as indicated, if desired.

g represents a pawl which is mounted in the body f of the projector and spring-pressed into engagement with a notch in the plunger 75 f³, so that the instant the plunger is drawn back to the position shown in Fig. 3 the pawl engages the plunger and holds it. For releasing this pawl I employ a pin h, which is vertically moved into and through the cap f' 80 of the projector and upon being pressed down throws the pawl out of engagement with the plunger and permits the spring f⁶ to impart a quick movement to the plunger. This movement is abruptly arrested by the engagement 85 of the finger-piece f⁴ with the side of the projector-body, and then the ball is shot along the way a².

The game apparatus may be used in any way and according to any rules desired. It 90 is best adapted, however, to the well-known game of bowling, and I prefer to employ it in this connection.

Various changes in the form, proportions, and minor details of my invention may be resorted to without departing from the spirit and scope of my invention. Hence I consider myself entitled to all such variations as may lie within the scope of my claims.

Having thus described my invention, I 100 claim as new and desire to secure by Letters Patent—

1. A projector for a game apparatus, comprising a body, a part of which is formed with

a double-tapered or hour-glass-shaped slot, a sustaining-bar passed through the slot, and a plunger carried by the body.

2. A projector for a game apparatus, comprising a body, a part of which is formed with a double-tapered or hour-glass-shaped slot, a sustaining-bar passed through the slot, a plunger carried in the body, a spring actuating the plunger in one direction, and a device for

releasably holding the plunger against the spring.

In testimony whereof I have signed my name to this specification in the presence of two subscribing witnesses.

DANIEL SMITH.
